CLAIM

The ornamental design of a putting practice device, as shown and described.

DESCRIPTION

FIG. 1 is a perspective view of a putting practice device showing our new design.

FIG. 2 is a top plan view of the device of FIG. 1.

FIG. 3 is a side elevational view thereof; the opposite side being a mirror image thereof.

FIG. 4 is a bottom view thereof.

FIG. 5 is a top edge view thereof; and,

FIG. 6 is a bottom edge view thereof.

1 Claim, 2 Drawing Sheets
